UNITED STATES PATENT OFFICE

FRED I. JADEN, OF HASTINGS, NEBRASKA

PRESSURE OILER

Application filed January 30, 1930, Serial No. 424,671. Renewed July 13, 1932.

This invention relates to oilers and particularly to oilers of the pressure discharge type.

One of the objects of the invention is the provision of an oiler that can be operated alternatively in the same manner as an ordinary pressure oiler, by pressure applied between the plunger handle and the reservoir, or by pressure transmitted to the plunger handle through the spout of the oiler by pressing the latter against the object to be oiled.

Another object of the invention is the provision, in the body or reservoir of the oiler, of a plunger cylinder supported by a universal connection at one end, and otherwise solely supported by the plunger itself, so that the cylinder accommodates itself to slight misalignment of the plunger rod, thereby avoiding binding and permitting the use without undue friction, of a plunger rod of uniform diameter throughout.

Still another object of the invention is the novel pump construction, the same comprising a valved fitting rigidly supported, and the plunger cylinder connected to said valved fitting by a sealed ball joint.

A further object of the invention is to provide a valved partition adjacent the forward end of the reservoir forming an anterior chamber intersected by the valved fitting for trapping a body of oil, making it accessible to the pump when the oiler is positioned spout upward, said partition constituting at the same time an inboard support for the valved fitting making the mounting of this member absolutely rigid, this being an essential factor in adapting the construction to transmit the operating pressure through the spout to the plunger rod.

Other objects of the invention will appear as the following description of a preferred embodiment thereof proceeds.

In the drawings in which the same characters of reference are employed through the several figures to denote identical parts:

Figure 1 is a longitudinal section through my improved oiler;

Figure 2 is a longitudinal section on an enlarged scale through the valved fitting and the adjacent parts of the oiler;

Figure 3 is a vertical section through the upper part of the oiler;

Figure 4 is an enlarged transverse section taken along the line 4-4 of Figure 3;

Figure 5 is a vertical section taken along the line 5-5 of Figure 4;

Figure 6 is a section taken along the line 6-6 of Figure 5 showing the hinged construction related to the valved partition;

Figure 7 is a perspective view of the valved partition;

Figure 8 is a perspective view of the hinged valve, a part of the partition itself being also shown;

Figure 9 is a perspective view of the inner end of the plunger cylinder; and

Figure 10 is a cross section taken along the line 10-10 of Figure 1.

Referring now in detail to the several figures, the oiler comprises a body or reservoir 1 constituted preferably by a cylindrical side wall 2 having inner and outer headers 3 and 4, respectively. A bolt 5 passes preferably axially through the reservoir having its head and nut engaging the outer faces of the headers for holding the latter rigidly in position. Suitable oil-tight gaskets 6 are compressed between the edges of the cylindrical member 2 and the inner face of the headers.

A disk-like partition 7 is arranged in the reservoir adjacent its anterior end and defines a chamber of relatively small size in which a body of oil is trapped and retained so as to be available for pumping when the oiler is positioned with its anterior end upper-most. For the purpose of trapping and retaining the oil, the partition 7 as shown in Figures 4 to 7, is provided with an opening or port 8, closed by a hinged check valve 9,

the latter opening toward the restricted chamber.

Although the specific construction of the valve 9 is a relatively minor part of the invention, yet at this point it may be stated that the partition 7 is formed with a slot 10 and a lug 11 at the central part of said slot, pressed out from the material of said partition on the side of the partition opposite the valve. The valve 9 is formed with two pairs of lugs 12 and 13, all four of said lugs being passed through said slot toward the side of the partition opposite the valve and then being bent to the position shown in Figures 5 and 8 so as to prevent their withdrawal from the slot. The lugs 12 act as a limit stop to the opening movement of the valve 9.

The oiler is provided with a handle 14 suitably secured to the header 4 and extending preferably above the axis of the reservoir, leaving room below said handle for the plunger rod 15.

Said plunger rod operates through a stuffing gland 16 in the header 4 and in cooperation with a pump cylinder 17. The plunger rod is normally retracted by means such as the spring 18 which expands between the end of the cylinder 17 and a collar 19 fixed to the plunger rod. The cylinder 17 is mounted by means of a fluid-tight ball joint 20 in the end of a valved fitting 21, the latter being rigidly supported.

By this construction the cylinder 17 can rock slightly in any direction about the ball joint so as to preserve its condition of alignment with the plunger rod 15, regardless of any slight misalignment of the plunger rod, either incident to its construction or through the pressure, in its use. The flexibility of the cylinder 17 enables a very cheap construction of plunger rod to be efficiently used, since the plunger rod may be made of plain stock of uniform diameter throughout without undue friction or binding in the cylinder.

By having the plunger rod of uniform diameter through a great extent of its length, a sealing joint of extensive length is provided within the cylinder 17 permitting considerable tolerance between the cylinder and plunger rod without the risk of loss of pressure. By this means, wear of the coating faces of the cylinder and plunger rod is minimized and long life of the oiler thus assured.

The valved fitting 21 is supported at one end by the header 3 and at the other end by the partition 7, the latter having a hole 22, Figure 7, into which the valved fitting extends. Said fitting is formed at its outer end with a shoulder abutting the header 3 and a nut 23 screws upon the adjacent end of said fitting at the outer end securing the fitting in place. On account of the fitting having a support at each end, it is supported with extreme rigidity and no bending stress is com-

municated to the ball end of the cylinder 17 in the use of the oiler.

The outer end of the fitting 21 is furnished with a spout 24 and a gland 25 the latter having a spherical seat 26 for receiving the ball end 27 of the tip 28. A ring nut 29 screws upon the gland 25 and against the ball end 27 so as to seat the latter in a fluid-tight manner in its seat within said gland. The opening in the ring nut is slightly larger than the diameter of the tip where it passes through the ring nut thus permitting a limited amount of universal movement between the tip and the spout. Thus the tip may be made to align itself with oil holes which are not in exact parallelism with the axis of the oiler.

The valved fitting 21 is provided with an inlet check valve 30 and an outlet check valve 31. The inlet check valve is very close to the lower wall of the restricted chamber formed between the partition 7 and header 3 so that the pump will suck practically the last drop of oil in the restricted chamber.

The inlet valve is preferably seated in a cage 32 which may be removed for cleaning or replacement, and the outlet valve is retained in a valve chamber in the end of the valved fitting by means of a spring 33 supported by a spider 34. By unscrewing the spout from the valved fitting, the spider and the valve may be readily taken out.

In order to prevent possible rotation of the entire body or barrel of the gun about the axis of the plunger, when the handle 14 is not held, it is advantageous to provide a yoke 35 clamped to the plunger rod at a suitable point within the body and having the sides thereof embracing the bolt 5 and freely slidable relative thereto.

It is obvious from the above description that the oiler may be operated in either of two ways, first in a manner well known in oilers, that is to say, by squeezing the plunger handle and the handle of the reservoir together, thus depressing the plunger. In this mode of operation, there is no strain upon the spout, valved fitting or the plunger cylinder 17. The other mode of operation which is known in respect to heavy grease guns, but has not heretofore been successfully practiced with liquid oilers, is to rest the tip against the wall of the aperture to be oiled and then to press against the plunger handle without holding the reservoir handle. In this instance, pressure is transmitted through the tip, spout and cylinder, and in the absence of special provisions for resisting this pressure thrust, there is apt to be a deflection between the plunger rod and cylinder causing binding between the parts and also a tendency of the valved fitting to be deflected, resulting eventually in a loosening of the joint between the valve fitting and the outer heading.

In the present invention the provision of the inboard support for the valved fitting en-

sures rigidity, while the ball connection between the cylinder 17 and the valve fitting provides sufficient flexibility on the part of the cylinder 17 to avoid any binding or excess friction due to the cause mentioned.

The provision of a fluid-tight ball joint between the tip and the spout also enables the oil to be injected into oil holes, however located, without loss of pressure between the tip and oil hole should the latter be at an angle to the tip when the oil is supplied.

It is clear that whenever the anterior end of the reservoir is directed downwardly, the restricted chamber between the partition 7 and the header 3 will be filled with oil through the valve 9 and that when the anterior end of the oiler is directed upwardly a body of oil will be retained in said restricted chamber sufficient to supply the pump while the oiler is in this position.

While in the above description, I have endeavored to describe what I believe to be a practical and preferred embodiment of my invention, it is to be understood that the details of construction as shown are merely by way of example, and not necessarily limitative in their bearing upon the invention, and that the scope of the invention is to be determined by a fair interpretation of the terms of the appended claims.

What I claim is:

1. Pressure oiler comprising a reservoir, a pump in said reservoir in communication therewith including a plunger rod and a cylinder therefor, a hollow swivelled joint supporting said cylinder at the end remote from said plunger rod and forming a conduit communicating with said cylinder.

2. Pressure oiler comprising a reservoir, a pump in said reservoir including a plunger rod of uniform diameter throughout and a cylinder therefor, and a fluid conducting member, there being means connecting the cylinder to the fluid conducting member for swivelled movement with respect thereto and having a passage establishing communication between the fluid conducting member and the cylinder.

3. Pressure oiler comprising a reservoir, a pump in said reservoir including a plunger rod slidably mounted at one end of said reservoir, and a valved fitting mounted at the other end having an intake communicating with said reservoir, a plunger cylinder intermediate said valved fitting and plunger rod, and a swivel joint connecting said cylinder and valved fitting.

4. Pressure oiler comprising a reservoir, a pump in said reservoir including a plunger rod slidably mounted at one side of said reservoir, and a valved fitting rigidly mounted at the other end having an intake communicating with said reservoir, a plunger cylinder intermediate said valved fitting and plunger rod, said cylinder being supported

at one end by said plunger rod and a swivel joint at the other end of said cylinder connecting it with said valved fitting.

5. Pressure oiler comprising a reservoir, a pump in said reservoir including a plunger rod slidably mounted at one side of said reservoir and a valved fitting supported at the other end having an intake communicating with said reservoir, a partition in said reservoir forming a chamber about said valved fitting, said partition forming a support for the said valved fitting, a plunger cylinder intermediate said valved fitting and plunger rod, the latter forming the support for one end of said cylinder and a swivel joint connecting said cylinder and valved fitting.

6. Pressure oiler comprising a reservoir, a pump in said reservoir including a plunger rod slidably supported at one end of said reservoir and a valved fitting supported at one end by the other end of said reservoir, a partition in said reservoir forming a chamber about said valved fitting, said partition being provided with a check valve controlled opening for trapping oil in said chamber, said partition forming a support for the opposite end of said valved fitting, a plunger cylinder intermediate said valved fitting and plunger rod and being supported at one end by said plunger rod, and a swivel joint connecting said cylinder and valved fitting.

7. Pressure oiler comprising a reservoir, a pump in said reservoir including a plunger rod slidably supported at one end of said reservoir and a valved fitting supported at one end by the other end of said reservoir, a plunger cylinder intermediate said valved fitting and plunger rod, the latter affording a support for one end of said cylinder, a swivel joint connecting said cylinder and valved fitting, a spout communicating with said valved fitting, intake and discharge valves carried by said valved fitting for sucking oil from said reservoir and discharging it from said spout, the latter being formed in rigid sections connected by a swivel joint.

8. Pressure oiler comprising a reservoir, a pump in said reservoir including a plunger rod slidably supported at one end of said reservoir and a valved fitting supported at one end by the other end of said reservoir, a plunger cylinder intermediate said valved fitting and plunger rod, the latter affording a support for one end of said cylinder, a swivel joint connecting said cylinder and valved fitting, a spout communicating with said valved fitting, intake and discharge valves carried by said valved fitting for sucking oil from said reservoir and discharging it from said spout, said spout including a tip section and a swivel fluid-tight joint connecting said tip section to said oiler.

9. Pressure oiler comprising a reservoir, a pump in said reservoir including a plunger

rod slidably supported at one end of said reservoir and a valved fitting supported at one end by the other end of said reservoir, a partition in said reservoir forming a chamber about said valved fitting, said partition forming a support for the opposite end of said valved fitting, a plunger cylinder intermediate said valved fitting and plunger rod the latter affording the sole support for one end of said cylinder, a fluid tight ball joint connecting the opposite end of said cylinder with said valved fitting, a spout for said oiler communicating with said valved fitting, said spout having a tip section and a ball joint connecting said tip section with said oiler.

10. In a pressure oiler, a pressure transmission line comprising a spout having a movable tip section connected by a swivel joint, a valved fitting, a cylinder and a plunger rod, said elements being operably arranged in series, said cylinder being solely supported at one end by said plunger rod and at the other end by a swivel joint connected to said valved fitting, and a reservoir communicating with said valved fitting, the latter having a suction valve in the connection to said reservoir and a discharge valve in the connection to said spout.

11. In a pressure oiler, a pressure transmission line comprising a spout having a movable rigid tip section connected by a swivel joint, a valved fitting, a cylinder and a plunger rod, said elements being operably arranged in series, said cylinder being solely supported at one end by said plunger rod and at the other end by a swivel joint connected to said valved fitting, and a reservoir communicating with said valved fitting, the latter having a suction valve in the connection to said reservoir and a discharge valve in the connection to said spout, said reservoir affording a rigid support for said valved fitting.

12. In a pressure oiler, a pressure transmission line comprising a spout having a movable rigid tip section connected by a swivel joint, a valved fitting, a cylinder and a plunger rod, said elements being operably arranged in series, said cylinder being solely supported at one end by said plunger rod and at the other end by a swivel joint connected to said valved fitting, and a reservoir communicating with said valved fitting, the latter having a suction valve in the connection to said reservoir and a discharge valve in the connection to said spout, a partition in said reservoir, said reservoir and partition affording supports for rigidly supporting said valved fitting at both ends.

13. In a pressure oiler, a pressure transmission line comprising a spout having a movable tip section connected by a swivel joint, a valved fitting, a cylinder and a plunger rod, said elements being operably arranged in series, said cylinder being solely

supported at one end by said plunger rod and at the other end by a swivel joint connected to said valved fitting, and a reservoir communicating with said valved fitting, the latter having a suction valve in the connection to said reservoir and a discharge valve in the connection to said spout, said reservoir and plunger rod having handles arranged perpendicularly to the direction of reciprocation of said plunger rod and in operative adjacency.

In testimony whereof I affix my signature.
